[57] **CLAIM**

The ornamental design for can crusher, as shown.

DESCRIPTION

FIG. 1 is a top, front and left side perspective view of a can crusher showing my new design on an enlarged scale;

FIG. 2 is a rear elevational view;

FIG. 3 is a right side elevational view;

FIG. 4 is a top plan view;

FIG. 5 is a bottom plan view;

FIG. 6 is a top, front and left side perspective view of a second embodiment of FIGS. 1-5 of my new design, shown on an enlarged scale;

FIG. 7 is a rear elevational view;

FIG. 8 is a right side elevational view;

FIG. 9 is a top plan view; and

FIG. 10 is a bottom plan view thereof.

FIG. 1

FIG. 2

FIG. 4

FIG. 5

FIG. 3

FIG. 6

FIG. 9

FIG. 8

FIG. 7

FIG. 10
